UNITED STATES PATENT OFFICE.

RICHARD W. ROBERTS, OF WASHINGTON, DISTRICT OF COLUMBIA.

INKING-PAD RECEPTACLE.

No. 876,398.

Specification of Letters Patent.

Patented Jan. 14, 1908.

Application filed April 14, 1906, Serial No. 311,790.

To all whom it may concern:

Be it known that I, RICHARD W. ROBERTS, a citizen of the United States, residing at Washington, in the District of Columbia, have invented new and useful Improvements 5 in Inking-Pad Receptacles, of which the following is a specification.

My invention relates to inking pad receptacles, and its primary object is to provide 10 a novel and highly useful means for returning the cover of the receptacle to its closed position upon the completion of each operation of inking a stamp so as to prevent dust entering the receptacle and settling upon the inking pad and the evaporation of the ink.

A further object is to provide a device of 15 the character stated wherein the means for returning the cover to its closed position has such relation to the cover as to present only sufficient resisting power as will be required 20 for the prompt return of said cover to its original or closed position.

A further object is to mount said means 25 upon the receptacle in a manner to permit it to be easily and quickly thrown into inoperative position in order that the cover may be thrown into position to be retained open when work is being done which requires the inking of the stamp at the maximum speed of manipulation.

A still further object of the invention is to 30 provide a finger piece by means of which the cover may be opened readily and quickly, which is adapted to be bent down so as not to form an obstruction to the packing of the 35 receptacle for shipment and by means of which the cover may be secured in closed position for the purpose of shipment.

With the above objects in view, the invention 40 consists in the construction, combination and arrangement of parts herein-after fully described, claimed and illustrated in the accompanying drawings, wherein:

Figure 1 is a perspective view of an inking 45 pad receptacle constructed in accordance with my invention, the cover being shown in closed position. Fig. 2 is a transverse central sectional view. Fig. 3 is a similar view 50 showing the manner in which the finger piece may be bent so as not to form an obstruction to packing, and to lock the cover in closed position. Fig. 4 is a view in end elevation, the cover being in opened position, and Fig. 5 is a detail perspective view of the means 55 for returning the cover to closed position.

Referring to the drawings by reference numerals, 1 designates a receptacle comprising a base 2, a cover 3, and 4 an inking pad carried by the base 2. The receptacle may be of any construction found desirable and may 60 be constructed of any material suitable for the purpose. The base 2 is of a weight sufficient to prevent it from being tilted by the opening of the cover 3, while the cover 3 is secured thereto by means of a hinge 5. 65

Secured to the rear side of the base 2 is a pivoted leaf spring 6, the same being secured to dispose its upper free end in opposition to and impinging lightly upon the rear end of the cover 3. This spring is adapted to permit 70 the cover to be opened a distance sufficient to permit a stamp to be inked and to return the cover to its closed position after the stamp has been inked. To accomplish this the said spring is movable on its pivot in 75 a plane parallel with the hinged edge of the cover. The free end of the spring is sufficiently flexible so that, while impinging upon the cover, it will not obstruct the initial opening movement of the cover, but will 80 offer sufficient resistance to return the cover to a slightly forward position beyond the vertical to cause the cover to gravitate to its closed position. The spring is provided with a perforation 7 through which may be let a 85

screw 8 to secure the spring in applied position. Only one screw is used and in view thereof, the spring may be moved to dispose its free end in such position that the cover may be thrown rearwardly beyond the vertical, whereby the cover will remain open and permit the maximum speed manipulation of the stamp to be inked without necessitating the opening of the cover every time it is desired to ink the same. A finger piece 95 9 is secured to the top of the cover 3 to project beyond its front edge and this projecting portion thereof may be curved or bent to any desired angle or position. When it is desired to open the cover, the under surface of 100 the finger piece 9 is engaged and an upward pressure exerted.

When it is desired to ship the receptacle the projecting portion of the finger piece is bent downward into engagement with the 105 edge of the receptacle, in which position the finger piece does not form an obstruction. The projecting portion of the finger piece is stamped up to provide a lug 10 which is caused to engage in a seat 11 in the edge of 110

the base 2, so that the cover may be locked in closed position. By bending the projecting portion of the finger piece the lug 10 is positioned for engagement with the seat 11.

5 In order to provide means by which the spring 6 may be thrown into inoperative position, said spring is stamped up to provide a projection 12.

10 It should be apparent from the above description, taken in connection with the accompanying drawings, that I provide means for returning the cover of an inking pad receptacle to its closed position upon the completion of each operation of inking a stamp, that said means may be readily and quickly thrown into inoperative position, that I provide a finger piece which is so constructed and has such relation to the cover that the cover may be readily and quickly opened 15 and which is adapted to lock the cover in closed position, and that my invention is simple and durable, and one which may be manufactured and sold at a comparatively low cost.

20 25 Changes in the form, proportions and minor details of construction may be made within the scope of the invention without departing from the spirit or sacrificing any of the advantages thereof.

Having fully described and illustrated my 30 invention, what I claim is:

An inking pad receptacle having a cover hinged to one side thereof at the upper edge of such side, and a spring pivoted at its lower end to such side for movement in a vertical 35 plane parallel with such side to dispose the free end of such spring either against such side of the receptacle, below the upper edge thereof, out of the way of the cover, or below such side to engage the hinged side of the 40 cover when the latter is open, said spring having an outwardly extending offset portion near the free end thereof to facilitate grasping of such spring and having its free end curved outwardly, the length of such spring 45 being such that the free end thereof projects beyond the outer side of the cover when the latter is open, and lies against the hinged side of the cover and wholly below the plane of the outer or upper surface thereof when 50 the cover is closed.

In testimony whereof, I affix my signature in presence of two witnesses.

RICHARD W. ROBERTS.
